UNITED STATES PATENT OFFICE.

JOSEPH J. HAYES, OF ELKHART, INDIANA.

TOWEL AND GARMENT HOLDER.

Application filed March 1, 1922. Serial No. 540,219.

To all whom it may concern:

Be it known that I, JOSEPH J. HAYES, a citizen of the United States, residing at Elkhart, in the county of Elkhart and State 5 of Indiana, have invented certain new and useful Improvements in Towel and Garment Holders, of which the following is a specification.

This invention relates to towel or garment 10 holders, and has for one of its objects to simplify and improve the construction and increase the efficiency and utility of devices of this character.

Another object of the invention is to provide a device of this character which may be readily extended to increase the capacity of the holder to any required extent, by duplicating the supporting members.

With these and other objects in view the 20 invention consists in certain novel features of construction as hereinafter shown and described and then specifically pointed out in the claims, and in the drawings illustrative of the preferred embodiment of the 25 invention:—

Figure 1 is a front elevation of the improved device, partly in section.

Fig. 2 is a plan view of the same.

Fig. 3 is a detached perspective view of 30 the resilient and yieldable holding member.

Fig. 4 is a detached perspective view of the supporting bar.

Fig. 5 is an end elevation enlarged, of the 35 improved device extended to provide a plurality of the holding devices.

The improved device comprises a supporting bar 10, preferably of wood, and with recesses 11 in the ends.

Bearing on the upper face of the bar 10 is 40 a rod, represented as a whole at 12, and rigidly attached to the bar intermediate its ends as by staples 13, leaving the outer parts of the rod yieldably bearing on the bar. The rod 12 is downturned near its ends as represented at 14, and extending by the downturned portions through the recesses 11, and thence directed laterally as at 15 and thence upwardly as at 16 and terminating in an eye 17 to receive a screw 18 to enable the device to be attached to a wall or other supporting structure as indicated at 19.

By this means the bar 10 is supported 50 spaced from the wall 19 a distance corresponding to the lengths of the portions 15 of the holding rod.

Bent upwardly from the rod 12 at each

side of the fastening devices 13, are loops 20 to facilitate the insertion of the towel or the article or garment and indicated conventionally at 21.

With a device constructed as shown and described, a towel or like article, or garment of any form, may be suspended from the bar 10 by inserting two corners of the towel, or small portions of a garment, through the loops 20 and drawing the adjacent portions between the body portions of the rod and toward the ends of the bar, as represented in Fig. 1.

The resiliency of the rod will be sufficient 70 to hold the towel or other article against the ordinary pull exerted while using the towel or to support a garment against its weight.

If a duplication of the holders is desired, 75 the portions 16 of the device may be coupled to another of the bars 10, and the portions 16 of the second bar attached by the screws 18 to the wall 19, as shown in Fig. 5. In the same manner any required number 80 of the bars 10 and rods 12 may be connected as will be obvious.

The towels or other articles or garments may thus be suspended in spaced relation, so that they do not interfere with each other 85 or come in contact while on the hangers.

The improved device is simple in construction, may be constructed of any size and of any suitable material, and of any length to correspond to towels or garments 90 of any size or form.

The preferred embodiment of the invention is disclosed in the drawings and set forth in the specification, but it will be understood that modifications within the 95 scope of the claimed invention may be made in the construction without departing from the principle of the invention or sacrificing any of its advantages:—

Having thus described the invention, what 100 is claimed as new is:

1. A device of the class described comprising a supporting bar, having an outwardly opening recess in one end, a rod of resilient material bearing upon said bar, said rod being downturned at the outer end to enter said recess and thence directed laterally and adapted to be connected by the laterally directed portion to a stationary support.

2. In a device of the class described a 110 supporting bar having outwardly opening recesses at the ends, a rod bearing upon said

bar and with downturned portions engaging in said recesses, the parts of the rod in advance of the downturned portions being directed laterally and coupling the rod to the bar thereby and adapted to be attached to a support.

3. In a device of the class described a supporting bar having outwardly opening recesses at the ends, a rod bearing upon said bar and with downturned portions engag-

ing in said recesses, the parts of the rod in advance of the downturned portions directed laterally and coupling the rod to the bar thereby and adapted to be attached to a support, said rod having outward loops intermediate the ends and attached to the bar adjacent to the loops. 15

In testimony whereof, I affix my signature hereto.

JOSEPH J. HAYES.
